DESIGN FOR A HANDBAG

Samuel R. Goldsmith, New York, N. Y.

Application December 3, 1938, Serial No. 81,535

Term of patent 3½ years

To all whom it may concern:

Be it known that I, Samuel R. Goldsmith, a citizen of the United States and resident of New York city, in the county and State of New York, have invented a new, original, and ornamental Design for a Handbag, of which the following is a specification, reference being had to the accompanying drawing, forming a part thereof, and of which—

Fig. 2 is a view thereof in end elevation; and
Fig. 3 is a top plan view thereof.

I claim:

The ornamental design for a handbag, substantially as shown.

SAMUEL R. GOLDSMITH.
